UNITED STATES PATENT OFFICE.

MARY E. PORTER, OF SYRACUSE, NEW YORK.

FOLDING SHELF FOR IRONING MACHINES.

Application filed July 24, 1924. Serial No. 727,933.

To all whom it may concern:

Be it known that I, MARY E. PORTER, a citizen of the United States of America, and a resident of Syracuse, in the county of 5 Onondaga, in the State of New York, have invented new and useful Improvements in Folding Shelves for Ironing Machines, of which the following, taken in connection with the accompanying drawings, is a full, 10 clear, and exact description.

This invention relates to a sectional folding table for ironing machines in which flat work to be ironed is moved along and upon the table to a rotary feed roller which carries the work against a heated ironing member for laundering purposes, the upper surface of the table being disposed in substantially the same horizontal plane as the upper face of the feed roller while the heated ironing member is preferably located at the rear of the roller for pressing cooperation therewith.

In machines of this character, there is always more or less liability of the work becoming wound around and upon the feed roll unless stripped from the underside thereof before returning upwardly along the front side of the roller toward the feed table, and inasmuch as no suitable means as yet has 25 been provided for properly stripping the work from the roller, it becomes necessary for the operator to stop the machine, reverse the roller and unwind the articles therefrom and when all parts of the table are secured 30 in a fixed position relatively to the feed roller, this stripping operation is extremely difficult and somewhat dangerous.

The main object of my present invention is to divide the table transversely and 40 diagonally some distance from one end and to leave that end free so that it may be displaced for convenient access to the rollers for stripping the work therefrom, particularly when ironing thin flat work which is more 45 liable to adhere to the roller and to become wound thereon, than the heavier fabrics because the latter are more liable to fall from the underside of the roller by their own weight.

50 In other words, I have sought to make the table in sections divided transversely along a diagonal line, a greater distance from one end than from the other to hinge the longer section to the shorter section along said diagonal line in such manner that the longer section may be locked upwardly and out-

wardly away from the feed roller to permit access to the major portion of said roller for ironing the thin flat articles thereon against the heated pressure member thus permitting 60 the operator to observe the action of the work on the roller and to readily strip the same from the roller in case it should tend to wind thereon.

Other objects and uses relating to specific 65 parts of the device will be brought out in the following description.

In the drawings:—

Figure 1 is a perspective view of an ironing machine equipped with my improved 70 folding shelf, the dotted lines indicating portions of the movable section of the valve adjusted to different positions from its normal position shown by full line.

Figure 2 is a top plan of the detached 75 shelf, the dotted lines indicating the position of the movable section when unfolded.

As illustrated, this machine comprises a main supporting frame —1—, a feed roller —2— journaled on the frame and an ironing 80 block —3— together with a feeding table which is also mounted upon the main supporting frame —1— in a manner hereinafter described.

The heating drum or ironing block —3— 85 is preferably stationary and is provided with a concave face lying adjacent the rear face of the feed roller —2— for cooperation therewith in smoothing and ironing the articles as they are fed rearwardly by the 90 upper part of the roller.

Any suitable means may be employed for heating the member —3— which is preferably hollow and for this purpose is provided a pipe —5— adapted to be connected 95 to any source of heating fluid such as steam or gas.

The feeding table —4— constitutes the essential feature of this invention, and is normally supported in a horizontal frame 100 on the front of the main frame —1— directly in front of the upper portion of the feed roller —2— and parallel therewith for receiving the articles to be ironed and permitting them to be fed forwardly therefrom 105 into engagement with the upper face of the roller —2— which is preferably covered with suitable fabric for frictionally engaging and feeding the articles rearwardly and against the front face of the heated ironing member —3—.

In many instances, as for example, in

- ironing thin flat articles which are usually moist when fed across the top of the table —4— to the feed roller —2—, adhere to the surface of the roller to such an extent as to be carried entirely around and wound upon said roller necessitating stopping of the machine for unwinding the articles therefrom and in order that this operation of stripping or unwinding the articles from the roller 10 may be accomplished more conveniently and with greater facility without liability of injury to the operator, the table is made in sections so that one section may be displaced from its normal position for affording a 15 greater vision of the adjacent portion of the roller and permitting the articles which are liable to adhere to the roller to be observed and stripped by hand before they become entirely wound upon the roller.
- 20 This ability to displace a portion of the feeding table is best accomplished by dividing said table transversely nearer to one end than to the other end and hinging the two sections together in such manner that the 25 longer section may be folded upwardly, forwardly and laterally to rest flatwise upon the shorter section if desired, some distance to one side of the center of the machine where it is temporarily out of the way of 30 the operator as shown by horizontal dotted lines in Figures 1 and 2.

The shorter section as —6—, is preferably secured by any suitable fastening means not necessary to herein illustrate or describe, to the frame of the machine so as to lie in a substantially horizontal plane while the longer section as —4'—, is supported along

the diagonal line of division at —7— upon the adjacent end edge of the section —6—, the other end of the longer section —6'— 40 being loosely supported upon the adjacent side of the frame —1— so as to be capable of vertical rocking movement from a horizontal position at one side of the diagonal division to a horizontal position at the opposite side of the said division and upon 45 the upper face of the shorter section —6—.

Dividing the feeding table transversely and diagonally in the manner described, permits the longer section —6— to be 50 rocked from its normal horizontal position upwardly and away from the roller —2— so as to leave the major portion of the roller exposed to the view of the operator particularly when ironing thin flat articles, all of 55 which enables the operator to strip these articles from the roller in case they should tend to wind thereon and to allow them to fall into the underlying tray as —8—.

What I claim is:

In an ironing machine having a feed roller for the articles to be ironed, a sectional table normally disposed parallel with and adjacent one side of the roller, one of the sections being relatively longer than the 65 other section and hinged thereto to swing about an axis diagonal to the axis of the roller.

In witness whereof I have hereunto set my hand this 2nd day of July, 1924.

MARY E. PORTER.
